Des. 200,322
Patented Feb. 16, 1965

200,322

ISOMETRIC EXERCISE FRAMEWORK

Robert R. Spackman, Jr., and Marvin E. Johnson, Carbondale, Ill., assignors to Southern Illinois University Foundation, Carbondale, Ill., a corporation of Illinois

Filed July 15, 1963, Ser. No. 75,793

Term of patent 14 years

(Cl. D34—5)

FIG. 1.

FIG. 2.

FIG. 3.

FIG. 1 is a top plan view of isometric exercise framework embodying our new design;

FIG. 2 is a front elevation of FIG. 1; and

FIG. 3 is a reduced perspective view of our isometric exercise framework.

We claim:

The ornamental design for isometric exercise framework, substantially as shown.
